UNITED STATES PATENT OFFICE

118,641

DESIGN FOR AN IRONING MACHINE

Robert E. Maxant, Forest Park, Ill., assignor to
Maxant Button and Supply Company, Chicago,
Ill., a corporation of Illinois

Application November 10, 1939, Serial No. 88,187

Term of patent 7 years

To all whom it may concern:

Be it known that I, Robert E. Maxant, a citizen of the United States, having residence in the village of Forest Park, county of Cook, and State of Illinois, have invented a new, original, and ornamental Design for an Ironing Machine, of which the following is a specification, reference being had to the accompanying drawing forming a part thereof.

In the drawing:

Figure 1 is a perspective view of an ironing machine embodying my new design.

Figure 2 is a top plan view of the same.

I claim:

The ornamental design for an ironing machine, substantially as shown.

ROBERT E. MAXANT.
